ADVERTISING SIGN

Filed March 28, 1928

2 Sheets-Sheet 2

By Clarence A. O'Brien, Attorney

UNITED STATES PATENT OFFICE.

BOTCHER H. WATKINS, OF DURHAM, NORTH CAROLINA.

ADVERTISING SIGN.

Application filed March 28, 1928. Serial No. 265,502.

The present invention relates to an advertising sign and aims to provide a device of this nature simulating a coffee pot and the prime object of the invention resides in the provision of a sign of this nature which is simple in its construction, strong and durable, inexpensive to manufacture and set up and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of the design embodying the features of my invention,

Figure 2 is a top plan view therethrough,

Figure 3 is a detail section taken substantially on the line 3—3 of Figure 1,

Figure 4 is a detail section taken substantially on the line 4—4 of Figure 1,

Figure 5 is a detail section taken substantially on the line 5—5 of Figure 1, and

Figure 6 is a detail section taken substantially on the line 6—6 of Figure 1.

Referring to the drawing in detail it will be seen that the numerals 5 denote a plurality of uprights arranged in a circular manner and inclining upwardly toward each other. These angle iron uprights 5 may have their lower ends in concrete bases 6 embedded in the ground. On the upper portions of the uprights 5 there is mounted a frusto-conical body A with a cover C on the top thereof, a spout simulating member projecting therefrom and braced as at 6 and a handle simulating member H on the side opposite the spout simulating member S.

The body A is formed in a plurality of sections 7 curved transversely and having one side edge formed with an inwardly extending channel flange 8 and the other side edge formed with an inwardly directed flange 9. The flanges 9 are adapted to be received in the channel flanges 8 and these flanges 8 and 9 are bolted together as at 10. The side edges of the sections 7 converge upwardly toward each other so as to give the body A the frusto-conical formation when the sections are fixed together.

On the inner surface of each section 7 there is disposed a band segment 12 against which is held a member 14 V-shaped in cross section.

The member 14, the band segment 12 and the section 7 are riveted together as at 15. Bolts 16 extend through the sections, the band segments, the member 14 and the angle iron 5 so as to anchor these parts together in a secure manner.

The upper ends of the sections 7 are provided with outwardly disposed rolls or bead portions 17. The cover C comprises a conical shaped body 18 the base of which is formed with an outwardly directed channel flange 19 U-shaped in cross section and an insert cylinder 20 has its upper edge formed with an outwardly directed annular flange 21 received in the channel flange 19 and this member 20 fits down in the upper portion of the body A as is clearly illustrated in Figure 4.

The handle simulating member H includes the curved body terminating in downwardly projecting ends riveted as at 23 to one of the sections 7. In the present embodiment of the invention there are four of these sections 7 one having the handle simulating member H thereon and an opposite one having the spout simulating member S thereon. The handle simulating member H is formed with longitudinally extending ribs 24 with reinforcements 25 therein.

The sections 7, the spout simulating member S the handle simulating member H, and the cover C are constructed of sheet metal and may be stamped or otherwise formed in the manner indicated above. It is thought that the construction, utility, and advantages of this invention will now be quite apparent to those skilled in this art without a more detailed description thereof. The present embodiment of the invention is obviously capable of being manufactured at a relatively low cost and yet have the required strength and durability.

This embodiment, however, has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention, what

I claim as new is:

A sign of the class described comprising a plurality of uprights, a frusto-conical body

mounted on the upper portions of the uprights, said uprights being secured to the interior thereof, a conical cover for the upper end of the body, said body comprising a plurality of transversely curved sections having the side edges thereof converging upwardly toward each other, one side edge of each section having a channel flange and the other side edge having a flange, said flanges being inwardly directed, the second flanges being receivable in the first named flanges, means for securing the flanges together, a plurality

of band segments in the body associated with each section transversely thereof and fitting against the inner surface thereof, members of V-shaped sectional formation disposed against the inner surfaces of the segment, means securing the members, segments and sections together, bolts extending through the sections, segments, members and uprights to anchor them together. ¹⁵ ²⁰

In testimony whereof I affix my signature.

ROTCHER H. WATKINS.
